UNITED STATES PATENT OFFICE.

EDWARD H. MACK, OF BETHLEHEM, PENNSYLVANIA.

FEED ATTACHMENT FOR LATHES.

SPECIFICATION forming part of Letters Patent No. 670,430, dated March 26, 1901.

Application filed September 12, 1900. Serial No. 29,779. (No model.)

To all whom it may concern:

Be it known that I, EDWARD H. MACK, a citizen of the United States, residing at Bethlehem, in the county of Northampton and State 5 of Pennsylvania, have invented new and useful Improvements in Feed Attachments for Lathes, of which the following is a specification.

This invention relates to new and useful 10 improvements in feed attachments for lathes; and its primary object is to provide a device of simple construction which may be readily applied and whereby the cross-feed of the cutting-tool may be automatically operated 15 from the face-plate.

To these ends the invention consists in providing a face-plate with one or more studs or 20 projections having rollers thereon which are adapted to contact successively with a lever pivoted to a bracket which is secured to the bed of the lathe. A chain is connected to 25 the opposite end of the lever and extends under a pulley which is journaled upon the bracket. This chain is connected at a point adjacent to its opposite end to an arm of a ratchet which operates a cross-feed of ordinary construction.

The invention also consists in the further 30 novel construction and combination of parts hereinafter more fully described and claimed, and illustrated in the accompanying drawings, in which—

Figure 1 is a side elevation of a lathe, showing the attachment applied thereto. Fig. 2 35 is a front elevation of the attachment, showing the upper portion of the bracket broken away and the face-plate and lathe in section; and Fig. 3 is a similar view of a modified form.

Referring to the figures by numerals of reference, 1 is a face-plate, in one or more of the slots 2 of which is secured a stud 3, having a roller 4 mounted thereon. These studs are 40 adapted to contact successively with the end of a lever 5, pivoted within the forked upper end 6 of a bracket 7, which is secured to the bed 8 of the lathe. The opposite end of the lever 5 is secured to a chain 9, which is adapted to pass downward and under a pulley 10, 45 which is journaled upon a stud 11, extending from the bracket 7 at a point below the lever 5. Said chain then extends forward and en-

gages a hook 12, which is secured to an arm 13 of an ordinary cross-feed ratchet 14. It will thus be seen that as the face-plate 1 revolves the lever will be depressed by each roller 4 as the same contacts therewith, thereby causing the ratchet-arm 13 to swing back and forth. It will be understood that by varying the number of studs and rollers 3 and 4, respectively, the speed of the cross-feed may be readily regulated.

Should it be desired to reverse the movement of the cutting-tool, it is necessary to employ an attachment such as shown in Fig. 3. In said figure I have shown a pulley 15 journaled upon a stud 16, arranged upon the bracket 7 at a point above lever 5. It will thus be seen that as the face-plate revolves it will lift the lever, and as the chain passes over two pulleys instead of one the movement of the feed will be reversed.

In the foregoing description I have shown the preferred form of my invention; but I do not limit myself thereto, as I am aware that 75 modifications may be made therein without departing from the spirit or sacrificing any of the advantages thereof, and I therefore reserve the right to make all such changes as fairly fall within the scope of my invention. 80

Having thus fully described my invention, what I claim as new, and desire to secure by Letters Patent, is—

1. A feed attachment for lathes comprising a bracket, a pulley journaled thereon, a lever pivoted to the bracket, and a chain extending from said lever and around the pulley and adapted to be secured to the arm of a cross-feed ratchet.

2. The combination with a lathe having a 90 face-plate, of a stud secured to the face-plate, a bracket upon the lathe, a lever pivoted thereto and adapted to be contacted and depressed by the stud, a pulley journaled upon the bracket, a cross-feed, a ratchet to said feed, and a chain secured to the outer end of the lever and extending under the pulley and adapted to be secured to the arm of said ratchet.

3. The combination with a lathe having a 100 face-plate, of a stud upon said plate, a roller upon the stud, a bracket secured to the lathe, a lever pivoted thereto and adapted to be contacted and depressed by the roller, a stud ex-

tending from the bracket, a pulley journaled thereon, a cross-feed, a ratchet thereto, and a chain secured to the outer end of the lever and extending under the pulley and secured 5 to the arm of the ratchet.

4. The combination with a lathe having a face-plate, of a stud secured to said face-plate, a roller upon the stud, a bracket secured to the lathe, a lever pivoted thereto 10 and adapted to be contacted and depressed by the roller, studs upon the bracket, pulleys

journaled thereon, a cross-feed, a ratchet thereto, an arm to the ratchet, and a chain secured to the outer end of the lever and mounted upon the pulleys, said chain being 15 secured to the arm of the ratchet.

In testimony whereof I affix my signature in presence of two witnesses.

EDWARD H. MACK.
